UNITED STATES PATENT OFFICE.

WILLIAM S. DOUGHERTY AND WILLIAM H. FRANKLIN, OF MONTROSE, COLORADO.

DISH-WASHING MACHINE.

1,217,576.

Specification of Letters Patent. Patented Feb. 27, 1917.

Application filed March 6, 1916. Serial No. 82,480.

To all whom it may concern:

Be it known that we, WILLIAM S. DOUGHERTY and WILLIAM H. FRANKLIN, citizens of the United States, residing at 5 Montrose, in the county of Montrose and State of Colorado, have invented certain new and useful Improvements in Dish-Washing Machines, of which the following is a specification, reference being had to the accompanying drawings.

This invention relates to an improved washing machine and more particularly to a dish washer, the invention having for its primary object to provide means whereby 15 large quantities of dishes may be quickly and thoroughly washed.

It is another object of the invention to provide a dish washing machine primarily designed for use by boarding-housekeepers, 20 hotels and the like, which may either be manually or power-operated, and is so constructed that the water is directed upon all parts of the dishes to thoroughly cleanse the same.

25 It is a more particular object of the invention to provide a machine for the above purpose, including a water receiving tank or vessel, a basket rotatably mounted therein having an imperforate bottom wall and a 30 central upwardly tapering standard rising therefrom through which the soapy water is radially discharged upon the dishes in the basket.

35 It is a further general object of the invention to improve and simplify machines of the above character whereby the same are rendered highly reliable and efficient in practical operation though capable of manufacture at relatively small cost.

40 With the above and other objects in view, our invention consists in the novel features of construction, combination and arrangement of parts to be hereinafter more fully described, claimed and illustrated in the accompanying drawing, in which,

45 Fig. 1 is a vertical sectional view of a dish washing machine constructed in accordance with the preferred embodiment of our invention; and

50 Fig. 2 is a horizontal section taken on the line 2—2 of Fig. 1.

Referring in detail to the drawing, 5 designates the water receiving vessel or tank which may be of any desired capacity and 55 is provided at its bottom with a drain faucet indicated at 6.

The dish container is provided with a vertical wire mesh wall 7 which is suitably secured at its lower end to an imperforate, shallow, conical bottom wall 8. This bottom 60 wall is centrally provided with an opening surrounded by the vertical upwardly tapering hollow standard 9 which is formed at its upper end with a chambered head 10, the 65 annular wall of which is perforated, as indicated at 11. To the under side of the bottom wall 8, a spider 12 is suitably secured and is centrally formed with a sleeve 13 keyed or otherwise fixed to a vertical shaft 14. Bracing arms or bars 15 are secured at their 70 outer ends to the upper edge of the wall 7 of the dish container and are inclined upwardly therefrom and integrally connected by a collar or sleeve 16 engaged upon said shaft. The shaft 14 projects below the 75 spider 12 and is seated in a step bearing member 17 fixed upon the bottom wall of the tank or vessel 5.

Bearings 18 and 19 are mounted upon the upper edge of the tank 5 at diametrically 80 opposite points, the bearing 18 being hinged or pivoted as at 20 upon a bracket member fixed to the tank wall. The other bearing 19 is notched or recessed. A horizontal shaft 21 is rotatably mounted at one end in the 85 bearing 18 and is adapted to be seated at its other end in the recess of the bearing member 19. Upon this shaft, a bevel gear 22 is fixed and meshes with a similar gear 23 on the upper end of the vertical shaft 14. The 90 shaft 21 is equipped with a suitable operating crank 23 or may be provided with a wheel to receive a driving belt when the device is to be power-operated. The shaft 14 is sustained in a perpendicular position to 95 hold the gear 23 in mesh with the gear 22 by means of an angular arm indicated at 24, one end of which is loosely engaged upon the shaft 14 and the other end bifurcated to provide a seat for the shaft 21. 100

In the practical use of the invention, it will be understood that the soiled dishes are placed within the wire basket and are directed by the inclined bottom wall 8 against the outer vertical wall of the basket so that 105 they will receive the full benefit of the water ejected from the openings 11 in the head 10 of the central standard. The tank or vessel 5 is now filled with boiling water, and during the use of the device a slow fire may be 110 maintained beneath the tank. Thus the boiling water in a constant state of ebulli-

tion is forced upwardly by the generated steam through the hollow tapering standard 9 and is ejected with considerable force through the openings 11 upon the dishes. 5 It will be observed that the bottom 8 of the dish container is spaced to some distance above the bottom wall of the tank, and particles of soap are placed in this space. The shaft 21 is operated to constantly turn the 10 cage or basket during the washing of the dishes, and the soap particles being agitated as well as heated, it will be understood that the water is quickly rendered very soapy. This soapy water finds its way between the 15 dishes contained in the basket and as it is forcibly directed upon the dishes, all particles of food will be thoroughly removed. These particles will find their way outwardly between the mesh of the wire wall 7 and acc- 20 cumulate upon the bottom of the tank 5. It requires a very short time to thoroughly cleanse the dishes, and they may be readily removed by simply lifting the crank end of the shaft 21 and disengaging the gear 22 25 from the gear 23. Preferably, the water is first drained from the tank 5 and the dishes will be dried by the heat from the metal walls, if allowed to stand for a short time. The cage containing the dishes can then be 30 removed from the tank. For this purpose, a block and tackle may be used when the machine is of large capacity such as would be used in hotels, and by means of such block and tackle the dish containing basket can 35 be transferred to a rinsing tank containing clear water. As this is a perfectly obvious operation, it is not thought necessary to illustrate the same in the drawing.

From the foregoing description, it will be 40 seen that we have devised a very simple, desirable and efficient dish washing machine which may be inexpensively manufactured and sold, and can be serviceably employed for both private domestic use and in large 45 hotels.

While we have disclosed what we believe to be the present preferred embodiment of the device, it is to be understood that the same is susceptible of considerable modifica- 50 tion therein and we, therefore, reserve the privilege of adopting all such legitimate

changes as may be fairly embodied within the spirit and scope of the invention as claimed.

Having thus fully described our invention, what we desire to claim and secure by Letters Patent is:—

1. In a dish washing machine, a water receiving tank, a dish container having a perforate vertical wall and an imperforate, 60 shallow, conical bottom wall provided with an opening in its apex, a hollow tapering standard rising from said opening and closed at its upper end, said standard having a plurality of perforations in its wall at the 65 upper end thereof, a shaft rotatably mounted upon the base of the tank extending axially through said standard and above the same, radially disposed supports for said container fixed upon said shaft adjacent its 70 upper and lower ends, and an operating means geared to the upper end of said shaft to rotate said container.

2. In a dish washing machine, a water receiving tank, a dish container having a vertical wire mesh wall and an imperforate shallow conical bottom wall, said bottom wall having a central opening therein, a hollow tapering standard rising from said opening extending through the container, 75 said standard being provided upon its upper end with a head having a perforated annular wall, a vertical shaft extending through said standard, a spider secured to the under side of said bottom wall and fixed upon said 80 shaft, upwardly and inwardly inclined braces fixed at their outer ends to the upper edge of the container wall and connected by a bearing collar through which the shaft is disposed, a step bearing for the lower end of 85 said shaft fixed to the bottom wall of the tank, and an operating shaft geared to the vertical shaft to rotate said dish container.

In testimony whereof we hereunto affix our signatures in the presence of two wit- 95 nesses.

WILLIAM S. DOUGHERTY.
WILLIAM H. FRANKLIN.
